UNITED STATES PATENT OFFICE.

CHARLES C. SCHLAX, OF KANSAS CITY, MISSOURI.

SHOE-FITTING DISPLAY-STOOL.

1,185,724.

Specification of Letters Patent.

Patented June 6, 1916.

Application filed April 8, 1915. Serial No. 20,083.

To all whom it may concern:

Be it known that I, CHARLES C. SCHLAX, a citizen of the United States, residing at Kansas City, in the county of Jackson and State of Missouri, have invented certain new and useful Improvements in Shoe-Fitting Display-Stools, of which the following is a specification.

This invention relates to shoe fitting display stools and has for its object to produce a device of this character for displaying attractively samples of shoe polish, shoe laces and other goods or wares whereby to suggest to or remind a person having shoes fitted on such stools that such goods or wares are on sale in the store where the display stool is used.

Another object is to produce means for illuminating the display and means whereby the resting of one's foot upon the stool will complete an electric circuit, through a lamp for producing such illumination.

Another object is to produce a shoe fitting stool of the character described, of simple, strong, durable compact and ornamental appearance.

With these objects in view the invention consists in certain novel and peculiar features of construction and combinations of parts as hereinafter described and claimed, and in order that it may be fully understood reference is to be had to the accompanying drawing, in which:

Figure 1, is a perspective view of a shoe fitting stool embodying my invention. Fig. 2, is a central vertical longitudinal section of the stool. Fig. 3, is a transverse section of the stool. Fig. 4, is a diagram of the electric connections.

In the said drawing, 1 indicates the top, 2 the sides, 3 the ends and 4 the legs of a stool, it being understood, however, that the special construction of the body of the stool may be varied without affecting the invention.

5 is the customary inclined rest upon which one's foot is placed during the shoe fitting operation, and said rest is provided with a window 6—preferably glass—through which objects or advertisements located within a chamber 7 may be viewed. The chamber is preferably formed by said window, one of the end walls of the body of the stool, extensions of the side walls, and a cross piece or bottom 8, the extensions of the sides supporting the foot rest in the position

shown, and to give access to said chamber, the foot rest is hinged at its upper end at 9 to the body of the stool. To secure the foot rest in closed position, any suitable means may be employed, a simple connection being hooks 10 pivoted to the extensions of the sides 2 and eyes 11 secured to the underside of the foot rest and adapted for engagement by said hooks, as shown clearly in Fig. 3.

For artificially illuminating the chamber 7 so that the contents thereof may be readily seen, a small incandescent lamp 12 is secured to the cross piece or bottom of the chamber, 70 said lamp being in circuit with a wire 13, electrically connected at its opposite ends with a contact 14 and a spring contact plate 15. A contact 16 is adapted for engagement by contact plate 15 when the latter is depressed by a foot resting on the foot rest, and said contact 16 is connected by a wire 17 to a contact 18. The plate 15 is preferably secured upon the front or upper side of the foot rest 5 and the contact 16 is fastened to said foot rest. The contacts 14 and 18 are secured in the end of the body of the stool, which forms one of the walls of the chamber 7, and engaging said contacts 14 and 18 with a yielding pressure are the 80 spring terminals 19 and 20 of a dry battery 21 which underlies the top of the body of the stool between the side and end walls of the latter, and to detachably support said battery, it is slipped through a U-shaped 90 keeper 22, depending from the top 1, the keeper having a rearwardly projecting spring arm 23 terminating in a tooth 24 and a downwardly extending lip 25. The arrangement is such that the battery can be 95 slipped forwardly over the spring catch constituted by the parts 23 to 25 inclusive and through the keeper until the terminals 19 and 20 bear against the contacts 14 and 18, the catch springing upward as such adjustment of the battery is effected to hold the same in the position described.

In practice the foot rest, with the exception of its window, will preferably be covered with a suitable wear fabric, such as corrugated rubber, not shown, to prevent the finished soles of a new shoe from being scratched or marred by contact with the metal plate 15, it being understood that the spring plate will be of sufficient power to 110 prevent the covering strip mentioned from effecting contact normally between said plate

and contact 16, in order to not only conserve the power of the battery, but because it is desirable to illuminate the chamber only when a person having a shoe fitted places his foot upon the foot rest, as through the flashing of the light at such time, his attention will be attracted to the contents of the chamber.

From the above description it will be apparent that I have produced a shoe fitting stool embodying the features of advantage enumerated as desirable and which is obviously susceptible of modification in minor particulars without departing from the principle and scope or sacrificing any of the advantages of the appended claims.

I claim:

1. A shoe fitting stool having a foot rest, a chamber below the same, and a window through which the interior of the chamber may be viewed, in combination with an electric lamp arranged to illuminate the interior of the chamber, a suitable source of electric energy in circuit with said lamp, and a pair of normally separated parts in circuit with the lamp and battery, one of said parts being located on the foot rest so that pressure applied on the foot rest shall establish an electrical connection with the other of said parts and thus complete the circuit through said lamp.
2. A shoe fitting stool provided with an

inclined foot rest having a window and with a chamber back of said window, normally separated contacts mounted on the foot rest, a lamp always connected with one of said contacts, a pair of contacts, one of said pair being connected to the lamp and the other to the contact carried by the foot rest which is not connected with the lamp, and a removable battery supported by and under the stool and electrically connected to said pair of contacts.

3. A shoe fitting stool provided with an inclined foot rest having a window and with a chamber lying back of the window, an incandescent lamp in said chamber, a spring contact plate secured to the foot rest and adapted to be depressed by foot pressure, a contact for engagement by said contact plate when depressed, a dry battery detachably supported at the underside of the top of the stool, and electric connections between the battery, the lamp, said contact and said contact plate, for completing a circuit through the lamp when said contact and contact plate are in engagement.

In testimony whereof I affix my signature in the presence of two witnesses.

CHARLES C. SCHLAX.
